(57) **CLAIM**

The ornamental design for a filter manifold cap as shown and described.

DESCRIPTION

FIG. 1 is a first isometric view of a filter manifold cap; FIG. 2 is a second isometric view of a filter manifold cap; FIG. 3 is a first side elevational view of the filter manifold cap;

FIG. 4 is a second side elevational view of the filter manifold cap;

FIG. 5 is a third side elevational view of the filter manifold cap;

FIG. 6 is a fourth side elevational view of the filter manifold cap;

FIG. 7 is a top plan view of the filter manifold cap; and, FIG. 8 is a bottom plan view of the filter manifold cap. The broken lines in the Figures show portions of a filter manifold cap that form no part of the claimed design.
